ABSTRACT

A mechanism is disclosed for absorbing recoil shocks upon the discharge of any ordnance device having a high muzzle velocity, particularly, of the shoulder-support type. A separate movable member encloses the gunstock end and is coupled to spring-tensioned axially actuated means. The end member resting against the shoulder of the user remains substantially stationary while the remainder of the mechanism housed within the gunstock moves to absorb all the energy.

FIG. 5

FIG. 3

1
GUN RECOIL ABSORBER**BACKGROUND OF THE INVENTION****1. Field of the Invention**

The invention relates to ordnance devices and more particularly, to recoil absorbers for shoulder-supported firearms.

2. Description of the Prior Art

The prior art is replete with various schemes and structures for recoil absorption. In U. S. Pat. No. 3,208,179 issued Sept. 28, 1965 to J. Hrebicek, a mechanism is shown involving ramps and rollers coupled to movable means to provide a riding surface for a gunstock upon recoil. Such a mechanism is rather complex, expensive, and subject to frequent failure due to jamming. Wider acceptance has thereby been prevented.

Another example is disclosed in U. S. Pat. No. 3,604,138, issued Sept. 14, 1971 to Jack W. Wilson, in which a series of levers and springs are actuated sideways upon the incidence of the discharge of the firearm. The manner of absorbing the shock is somewhat awkward due to the change of direction of the forces which are actually in an axial direction. Further, the adaptation of the recoil absorber mechanism to existing devices is impossible and can only be incorporated into new units. Still another example is shown in U. S. Pat. No. 3,001,312, issued Sept. 26, 1961 to C. S. Campbell wherein a spring-actuated member is provided together with a liquid container. The difficulty with this structure resides in the fact that the method of anchoring the absorbing mechanism results in a jerking movement of the gunstock away from the shoulder of the user. This motion prevents accurate sighting and yields particularly poor results when telescopic lenses are used.

A need arises, therefore, for a positive acting recoil absorber which is inexpensive, simple to install, easy to operate and capable of absorbing high recoil velocities without reducing accuracy and effectiveness.

SUMMARY OF THE INVENTION

In accordance with the present invention a recoil absorber mechanism is disclosed having spring-tensioned lever-actuated means anchored within a cavity in a gunstock. The mechanism is adapted to reciprocate in an axial direction and is operatively associated with a hollow movable end member conforming to the shape and dimensions of an adjacent conventional wooden gunstock. This member may be fabricated of a durable, lightweight material, such as any of the well known thermoplastic materials and be clear or colored to match the gunstock coloring.

Compression of the spring-loaded members results in movement of a movable yoke arrangement including pivoted interconnecting lever arms in the opposite direction as the high velocity forces ejecting the projectile from the muzzle. Such movement effectively pulls the entire gunstock toward the movable end member which is resting against the user's shoulder. The entire pressure exerted by the recoil is spent in moving the solid gunstock in this manner and the end resting against the shoulder remains substantially stationary after firing.

Means are provided for adjusting the spring tension, confining the movement of the spring-loaded members and guiding the movement of the yoke arrangement.

2
Alternative embodiments include dual or single spring-loaded means.

BRIEF DESCRIPTION OF THE DRAWINGS

Details of the invention will be readily understood after consideration of the following description and reference to the accompanying drawings, wherein:

FIG. 1 is a partial cross-sectional of an embodiment of the invention before firing of the device;

FIG. 2 is a partial cross-sectional view of the embodiment shown in FIG. 1 after firing;

FIG. 3 is an elevation view taken along the line 3-3 in FIG. 1;

FIG. 4 is a fragmentary cross-sectional view taken along the line 4-4 in FIG. 1; and

FIG. 5 is a partial cross-sectional view of an alternative embodiment of the invention.

DESCRIPTION OF THE PREFERRED EMBODIMENTS

Referring now to FIGS. 1 and 2 a dual spring-loaded recoil absorber mechanism is illustrated. Gunstock 10 is provided with a main cavity section 12 of sufficient magnitude to permit free movement of the scissors-type recoil absorber mechanism 14. In addition cylindrical cavity sections 16 and 18 and an axial elongated passage 20 are provided in the gunstock 10. A final alteration required to the existing gunstock is the drilling of elongated holes 22 and 24 to accommodate guide rods 26 and 28. The main cavity section 12 is separated from the remaining cavities 16 and 18, passage 20 and holes 22 and 24 by an anchor plate 30.

Referring now to FIG. 3 as well as FIGS. 1 and 2 the arrangement of the recoil absorber mechanism 14 will be described. A central axial-reciprocating rod member 32 extends within passage 20 and aperture 34 in anchor plate 30. Suitable bushing means 33 are provided for longer wearing and to prevent binding. The outer end of rod 32 threadably engages hollow movable gunstock end member 38 having a shape to conform the conventional wooden gunstock 10. Member 38 may be made of a lightweight thermoplastic material. Alternatively, it is possible to provide a plain metallic plate shaped for comfort against the shoulder of the user which would resemble a T-shaped structure.

The recoil absorber mechanism 14 further includes spring-tensioned coaxial members 40 and 42 housed within cavities 16 and 18. Metallic cylinders 41 and 43 are provided to line the wooden walls of the cavities for improved operation. Each of members 40, 42 comprise central rods 44, 46 and springs 48, 50. The appropriate adjustment of spring tension to absorb the high velocity recoil forces is provided by plates 52, 54 and nuts 56, 58 secured to the inner end of rods 44, 46. Oval-shaped apertures 60, 62 in anchor plate 30 provide for introduction of rods 44, 46 and a means for restraining springs 48, 50 upon compression. The outer end of rods 44, 46 are connected as by peened pins 64, 66 welded to pivoted lever arms 68 and 70 to form a substantially scissors-type movable yoke arrangement resembling a caret (^) in the before-firing position and a V after firing.

The pivot arrangement to enable free movement of the yoke formed by lever arms 68, 70 will now be described by referring to FIG. 4. A slot 72 is machined in rod member 32. Each of the lever arms 68, 70 are also provided with a slot 74. A pin and rivet arrangement 76

together with washers 78 provides for interconnection of the lever arms. Intermediate washer 79 may be provided for ease of operation. To guide the movement of the gunstock 10 after firing in a direction towards the end member 38 parallel guide rods 26, 28 are intermediate disposed and attached to lever arms 68, 70 by pins 80, 82. The guide rods 26, 28 are disposed within holes 22, 24. The anchor plate 30 is secured to the gunstock cavity walls by means of four screws 84.

In FIG. 2 the spring-tensioned members 40, 42 are shown as compressed and it will be noted that lever arms 68, 70 of the recoil absorber mechanism 14 have now assumed an inverted or V-shaped configuration. All the recoil forces are absorbed by movement of gunstock 10 while the end member 38 resting against the shoulder of the user remains substantially stationary. The recoil forces can be adjusted for any rifle or shotgun by adjustment of the spring tension.

In FIG. 5 an alternative embodiment is shown incorporating a single spring-tensioned axial member 88 provided with cavity 89 having a rod member 90 and spring 92. Lever arms 94, 96 are provided with slots 98, 100 at each end of lever arms 94, 96 along with similar slots 102, 104 for joining them to central rod member 90. Parallel rods 106, 108 are provided within bushings 110, 112 and holes 114, 116. Rods 106, 108 are joined to lever arms 94, 96 and rods 106, 108 and 90. Guide rods 118, 120 are also provided in holes 122, 124. The hollow end member 38 is similar to the one shown in FIGS. 1 and 2 and only dual connection means 126, 128 are required. In this embodiment an opposite inversion configuration is provided. The tension is adjusted by nut 130 against plate 132.

There is thus disclosed a novel recoil absorber for all ordnance devices. Many variations and alterations will be evident to those skilled in the art. It is intended therefore that the foregoing described embodiments be considered in their broadest aspects and not in a limiting sense.

What is claimed is:

1. A recoil absorber mechanism for a gunstock comprising:
spring-loaded axially actuated means; housed within the gunstock;
means for limiting movement of said spring-loaded means;
means for actuating said spring-loaded means including a reciprocating member;
a movable yoke mechanism including interconnected arm members operatively associated with said reciprocating member and said spring-loaded means;
means for supporting the gunstock and recoil absorber means against the shoulder of a user affixed to the outer end of said reciprocating means; and
means for guiding movement of said arm members.
2. The mechanism according to claim 1 wherein said

shoulder supporting means comprise a hollow movable end member conforming to the shape of the associated gunstock.

3. The mechanism according to claim 2 wherein said hollow movable end member is formed of a lightweight thermoplastic material.

4. The mechanism according to claim 1 and means for adjusting the tension of said spring-loaded means.

5. The mechanism according to claim 1 wherein said reciprocating member is provided with a central slot to freely accomodate the ends of said arm members.

6. The mechanism according to claim 5 wherein said arm members ends are slotted and a pin member interconnects all the members in a scissors-type arrangement.

7. The mechanism according to claim 1 wherein said limiting movement means comprise an anchor plate secured to the gunstock with restricted apertures for said spring-loaded means and clearance apertures for said reciprocating member.

8. The mechanism according to claim 1 wherein said guiding means comprise rod members disposed within elongated holes disposed in said gunstock.

9. A recoil absorber mechanism for a gunstock comprising:

plural parallel disposed spring-loaded axially actuated members;
an anchor plate for limiting movement of said spring-loaded members secured to said gunstock;
a central reciprocating rod member;
a movable yoke mechanism including pivotally interconnected arm members operatively associated with said reciprocating member and each of said spring-loaded members;
a movable end member affixed to said central reciprocating rod member; and
guide rod means secured intermediately to the ends of said arm members.

10. A recoil absorber mechanism for a gunstock comprising:

a centrally disposed spring-loaded axially-actuated member;
an anchor plate for limiting movement of said spring-loaded member secured to said gunstock;
reciprocating rod members disposed parallel to said spring-loaded member;
a movable yoke mechanism including interconnected arm members operatively associated with each of said reciprocating members and said spring-loaded member;
a movable end member affixed to said reciprocating members; and
guide rod means secured intermediately to the ends of said arm members.
